UNITED STATES PATENT OFFICE.

ALEXANDER M. THOMSON AND JAMES E. TAYLOR, OF CHICAGO, ILLINOIS.

DESIGN FOR A LABEL.

Specification forming part of Design No. 7,082, dated December 30, 1873; application filed November 26, 1873.
[Term of Patent 14 years.]

To all whom it may concern:

Be it known that we, ALEXANDER M. THOMSON and JAMES E. TAYLOR, of the city of Chicago, county of Cook and State of Illinois, have invented a Design for Labels, of which the following is a specification:

The nature of our design is fully represented in the accompanying print, to which reference is made.

We propose to make it in four sections, representing the sides, back, and front of our package. Section No. 1 is represented by a plain ground of color, surrounded by a plain line-border, and bears upon its face the words "Warranted Nett Weight." Section No. 2 has for its center the arms of Great Britain, surrounded by an ornamental design composed of several lines, the two outer ones of which cross each other at the top and bottom of the design, and at the sides form a part of the plain line-border which surrounds the whole of this section. Above the central design in this section is the word "Taylor's," and upon a band or ribbon, which lies diagonally across the central design, is the word "English," and below which is the word "Mustard," substantially as shown. Section No. 3, like section No. 1, is a plain ground of color surrounded

by a plain line-border, and bears upon it the following words, viz: "Thomson & Taylor, agents for the United States." Section No. 4, like section No. 2, is surrounded by a plain line-border, and contains the following words, viz: "Taylor's English Mustard," and an ornamental design which surrounds the figure of a lion rampant, the word "Taylor's" being arranged at the top of the section, the word "English" in the center, immediately above the figure of the lion, and the word "Mustard" at the bottom, all substantially as shown.

We prefer to print it in colors; but do not consider the colors selected to be an essential feature of our design.

What we claim as our invention is—

A label composed of four sections, and the words "Warranted Nett Weight," "Taylor's English Mustard," and "Thomson & Taylor, agents for the United States," and the arms of Great Britain, and figure of a lion rampant, arranged as above specified, and shown in accompanying fac-simile.
